UNITED STATES PATENT OFFICE.

FRANCIS M. MATTESON, OF JACKSON, MICHIGAN.

FURNACE.

1,248,144.

Specification of Letters Patent. Patented Nov. 27, 1917.

Application filed March 20, 1917. Serial No. 156,125.

To all whom it may concern:

Be it known that I, FRANCIS M. MATTESON, a citizen of the United States, residing at Jackson, in the county of Jackson and State of Michigan, have invented certain new and useful Improvements in Furnaces, of which the following is a specification.

This invention relates to hot air furnaces and has for its object the provision of simple, inexpensive and efficient means whereby the heat generated in the furnace may be more advantageously utilized than with devices heretofore known to me.

The invention is illustrated in the accompanying drawings and consists in certain novel features which will be particularly pointed out in the claims following the description.

In the drawings:

20 Figure 1 is a perspective view of a furnace embodying my improvements, the outer casing being omitted;

25 Fig. 2 is a vertical transverse section through the furnace and the casing, the lower portion of the furnace body, together with the feeding pouch or pocket and the ash pit pouch or pocket, being shown in elevation.

30 The lower portion or body 1 of the furnace is preferably of cylindrical form and may be of any desired dimensions. In the upper end of the body 1, I fit a cup ring 2 which is constructed with an intermediate horizontal portion 3 adapted to rest on the 35 upper edge of the body and project laterally beyond the same, spaced concentric flanges 4 and 5 being provided on the upper side of this intermediate portion to receive the lower end of the upper section or radiator 40 6 of the furnace. This upper section or radiator will preferably be constructed of sheet metal and is also of cylindrical form, the metal sheet being rolled and having its ends brought together and riveted or otherwise rigidly secured, as shown at 7, suitable packing or calking being provided to prevent leakage in the joint. The flanges 4 and 5 should fit snugly to the lower end of the radiator and may be riveted or bolted 45 thereto. The provision of these flanges provides a firm support for the radiator and

also maintains the circular shape of the same. The upper end of the radiator receives a head 8 which will preferably be cast and is formed with a plurality of openings 9 defined by depending annular ribs or flanges 10, as clearly shown in Fig. 2. The head is also constructed with an annular depending flange 11 which fits snugly within the upper end of the radiator and thereby 55 serves to maintain the proper shape of the same, the radiator being secured to the said flange by rivets or bolts, as will be readily understood. Near the lower end of the radiator, I provide the same with a plurality of openings, corresponding in number with the openings in the head 8, and to the inner surface of the radiator, I secure the lower ends of elbows 12 which have their upper ends fitting within the openings defined by the depending ribs 10, as shown in Fig. 2. The lower ends of these elbows are provided with annular flanges 13 through which rivets or bolts are inserted to secure the elbows in place. To the outer side of 70 the radiator 6, by the same bolts or rivets which secure the elbows 12 thereto, I secure air-feeding tubes 14 which extend downwardly between the furnace and the casing 75 15 to points near the lower end of the furnace and the casing and have their lower extremities open, as shown at 16. The casing 15 is set up around the furnace and the said air-feeding tubes and is constructed and arranged at its lower ends in any desired manner to admit fresh air to the space between itself and the furnace. From the upper end of the casing flues 17, provided in any desired or necessary number, lead to different parts of the building which is to be heated. 80 85 90

The body 1 of the furnace is provided interiorly with a grate whereby it is divided into a fire box and an ash pit and to the outer side of the body I secure chutes 18 and 19 communicating, respectively, with the fire box and the ash pit. The grate may be of any desired form and equipped with any convenient form of mechanism for agitating it to precipitate the ashes from the fire box, but as these elements do not form 95 a part of my invention I have not illustrated the same in the drawings. The chutes 100

18 and 19 are securely bolted to the body 1 of the furnace and project laterally therefrom so that their open ends will register with the openings in the casing. Upon the 5 outer end of each chute is hinged a door 20 and upon one side of each chute is formed a lug or keeper 21 which projects through the casing and beyond the outer end of the chute to be engaged by a latch 22 carried by 10 the door. The chutes 18 and 19 are duplicates in construction and the casing extends over and is bolted to the outer ends of the chutes, the door closing against the casing and the casing being formed with door 15 openings corresponding to the open outer ends of the chutes.

The interior of the radiator 6 is unobstructed except for the elbows 12, and the smoke pipe 23 leads laterally from the lower 20 end of the radiator through the casing and extends to the chimney, as will be readily understood. To aid in holding the air feeding tubes 14 against dropping, I may provide bolts or other projections 24 thereon 25 at their upper ends and draw a wire 25 taut around them.

It is thought the operation and advantages of my improved construction will be readily understood. The fire is kindled in 30 the fire box in the usual manner and the smoke and other products of combustion, together with the heat arising from the fire, will pass upwardly into the radiator and will fill the same so as to circulate all 35 around the elbows and, consequently, raise the temperature of the same, the smoke and other waste products eventually escaping through the smoke pipe 23. The elbows 12 will be quickly heated by the hot air arising 40 from the fire and, consequently, the air which may be within said elbows will be set in circulation and will pass from the upper ends thereof into the space between the top of the radiator and the top of the 45 casing and thence enter the flues 17. Cold air from the lower portion of the space between the casing and the furnace will enter the lower ends of the feeding tubes 14 and will rise through the same and enter 50 the elbows 12 and take the place of the air passing from said elbows and as the said feeding tubes 14 will be exposed to the heat radiated by the furnace body, they will be quickly heated and, consequently, the air 55 passing through said tubes and the elbows 12 will be raised to a high temperature with a slight consumption of fuel and without interfering in any way with the heating of the air in the space between the casing 60 and the furnace in the usual manner. The radiator 6 will also be raised in temperature by the hot air which will rise into and be caught thereby so that heat will be radiated from said member to act on the air rising

through the space between the furnace and the casing. The air flowing to the several rooms from the furnace casing will be more thoroughly and highly heated than is the case with furnaces now known to me consuming the same quantity of fuel, and the 65 desired temperature of the rooms may be very economically maintained. My device is exceedingly simple in the construction and arrangement of its parts and may be manufactured and applied to furnaces at a 70 low cost. By mounting the doors to the feeding chute and the ash chute directly upon said chutes, I eliminate joints which, with furnaces as now commonly constructed, form openings which permit dust from the 75 ash pit to escape unnecessarily into the furnace room and also permit air to enter the fire box when such action is not desired. Moreover, the provision of separate door frames does not permit the use of such 80 strong latches as may be used in my device and the latch-retaining lugs on the door frames are exceedingly apt to be broken by 85 carelessness in opening and closing the doors.

While I prefer to construct the body of the radiator of sheet metal, because such material is inexpensive, light and quickly heated, other material may be used, and the radiator may be constructed of cast 90 metal. It is to be noted that the radiator with the elbows 12 and the head 8 may be assembled and the parts rigidly secured together and the assembled structure then placed in position in the cup ring 4, and 95 this facility of assembling the parts and then placing the assembled parts on the lower section or body of the furnace expedites the setting up of the furnace at the place where it is to be used. By providing 100 a suitable reducing ring to fit in the upper end of the furnace body, the radiator may be applied to any furnace.

Having thus described the invention, what is claimed as new is:

1. The combination with a furnace fire pot, of a sheet metal shell fitted to the upper end of said fire pot, a head secured in the upper end of said shell, elbows having their upper ends secured in and opening through said 115 head and provided at their lower ends with annular flanges secured to the sides of the shell around openings therein near the lower end of the same, air-feeding tubes provided at their upper ends with annular flanges 120 secured to the shell around the same openings and coincident with the lower ends of said elbows, and a connection between the upper ends of said air-feeding tubes external to the shell.

2. The combination with a furnace fire pot, of a shell fitted to and supported by the upper end of the fire pot, a head secured

in the upper end of the shell, a plurality of elbows having their upper ends fitted in and opening through said head and their lower ends secured to the shell near the lower end of the same, a plurality of air-feeding tubes secured externally to the shell and communicating directly with the lower ends of said elbows, projections on the upper ends of said air-feeding tubes, and a connection between the said tubes passing 10 around the said projections.

In testimony whereof I affix my signature.

FRANCIS M. MATTESON. [L.S.]
